PROCESS OF MANUFACTURING CAR-BURETED WATER GAS

William E. Steinwedell, Cleveland Heights, Ohio,
assignor to The Gas Machinery Company,
Cleveland, Ohio, a corporation of Ohio

Application April 6, 1938, Serial No. 200,448

5 Claims. (Cl. 48—208)

This invention particularly relates to improvements in the well-known methods of manufacturing carbureted water gas in a gas-making set including a generator, a carbureter, a superheater, and a seal, all connected in a well-known manner, and equipped with the usual fixtures such as pipes and valves for supplying suitable media for blasting a fuel bed in the generator, and for making up and down gas-making runs through the fuel bed, and for carbureting the water gas so made. My invention particularly relates to improvements in such processes in which the carburetion is effected by the use of heavy oil, such as bunker oil, and in which a down blasting is effected by admitting the blasting air at the top of the carbureter.

Also, preferably, the steam for the down run is admitted at the top of the generator, but it is within the spirit of my invention to admit such steam for the down or reverse run at the top of the superheater, and then pass the steam downwardly through the superheater and upwardly through the carbureter and thence to the top of the generator, for operation under the well-known back-run process of making carbureted water gas.

The invention is particularly applicable for working in that type of a carbureted water gas set in which the hot gas valves for controlling the direction of flow are located adjacent the seal, i. e., the setting of these valves determines through which one, of two pipes communicating with the seal, the gas flow should take place.

The annexed drawing and the following description set forth in detail certain steps illustrating my improved process, these steps constituting, however, but a few of the various series of steps by which the improved process may be carried out.

The figure is a view, partly in elevation and partly in vertical section, of apparatus for manufacturing carbureted water gas by the use of my improved method.

Referring to the annexed drawing, a generator A, a carbureter B and a superheater C constituting carbureting apparatus, and a seal D are connected together in the well-known manner by a pipe E between the top of the generator and the top of the carbureter, a pipe F between the bottoms of the carbureter and superheater, a pipe G leading from the stack C' of the superheater C to the seal D, and a by-pass pipe H from the bottom of the generator to the pipe G. Pipe I controlled by valve 1' feeds air into the bottom of the generator A, and pipes 2 and 11 controlled by

valves 2' and 11', respectively, feed air into the top of the carbureter B. Steam pipes 4 and 8 controlled by valves 4' and 8', respectively, feed into the air pipe I and the top of the generator A, respectively. An alternate steam pipe 9 controlled by valve 9' feeds into the pipe G. A pipe 5 controlled by valve 5' feeds heavy oil into the top of the generator A. The pipe G is controlled by an up-run hot gas valve 7 and the pipe H by a down-run hot gas valve 6. The superheater stack C' is controlled by a valve 3 and an additional stack 10 is provided which communicates with the pipe H and is controlled by a valve 10'. The dip of the pipe G into the seal D is in an amount sufficient to exceed the effect of the pressure in the stack C'.

The manner of using the afore-described apparatus, when working my improved process, consists in first preparing for forward or upward blasting by having all valves closed except the stack valve 3 and the up-run hot gas valve 7. Then the fuel bed in the generator A is blasted with air which is admitted by opening the valve 1', and the resultant blast gases which pass through the connection E from the generator A to the carbureter B are burned by air admitted by opening the blast valve 2', this burning of the blast gases suitably heating the checkerwork in the carbureter B and superheater C. The resultant products are discharged through the open valve 3 of the stack C'.

Then the carbureter blast valve 2' is closed and, in succession, the generator blast valve 1' and the superheater stack valve 3 are also closed, which places the apparatus in condition for an up-run.

This up-run is effected by first opening the steam valve 4' which effects the formation of the blue water gas by the passage of the steam through the heated fuel bed, which blue water gas is carbureted by heavy oil admitted by opening the valve 5', the heavy oil being sprayed upon the fuel bed and being cracked and volatilized and mixing with the blue water gas issuing from the fuel bed and being permanently fixed in the heated checker-brick of the carbureter B and superheater C. As has been stated, the hot gas valve 7 in the pipe G is open so that the resultant gases pass into the seal D through the pipe G. The up-run is terminated by first closing the oil valve 5' and then the up-run steam valve 4'.

Then a down-run is effected by first opening the down-run hot gas valve 6, then closing the up-run hot gas valve 7, and then opening the down-run steam valve 4', which results in the

formation of blue water gas by the passage of steam downwardly through the fuel bed, which blue water gas issues from the bottom of the generator and passes by pipe H into pipe G and thence into the seal D. The down-run is terminated by closing the steam valve 8'.

Then a down-blow is effected by first opening the valve 10' of the auxiliary stack 10, and then opening the blast valve 11' at the top of the carbureter B, which effects a down-blow through the fuel bed of the generator A, and the resultant products therefrom pass into the pipe H and thence into stack 10 and out through the stack valve 10'. The down-blow is terminated by closing the blast valve 11'. Then the up-run hot gas valve 7 is opened, the down-run gas valve 6 closed, the superheater stack valve 3 opened, and the stack valve 10' closed. Then the apparatus is in the same condition as was originally presented for forward blasting, and a cycle has been completed.

Under some conditions when working the improved process which has just been described, it may be deemed essential to effect a short blow-run during the up-blow. This may be effected by closing the superheater stack valve 3 before the bottom generator blast valve 1' is closed and thus terminate the up-blow period by a short blow-run.

Under some conditions, it may be deemed essential to add heavy oil to the fuel bed during part of the down-run, as well as to carburet the blue water gas during the up-run; in which case, the oil valve 5', instead of being closed at the termination of the up-run, can be allowed to remain open during part of the down-run, and then this oil valve 5' can be closed at any desired time after opening the down-run steam valve 8'.

Under some conditions, it may be desired to make a short down-blow run; in which case, the top generator blast valve 11', which furnishes the air for the blast downwardly through the fuel bed, may be opened, after the termination of the down steam run, and before the opening of the auxiliary stack valve 10', and thus the down-blow gases pass through the connections H and G to the seal D for a short period, and then the auxiliary stack valve 10' is opened.

As before stated, it is within the spirit of my invention to admit steam for the down or reverse run at the top of the superheater C through the pipe 9, instead of to the top of the generator A through the pipe 8, if it is desired to operate the gas-making set under the well-known back-run process of making carbureted water gas. In this event, the steam passes from the pipe 9 through the connection G and thence into the superheater C and carbureter B in succession, whence it passes through the pipe E into the top of the generator A and downwardly through the fuel bed in the operating manner before described with reference to the ordinary admission of steam through the pipe 8 to the top of the generator A.

65 What I claim is:

1. The process of manufacturing carbureted water gas, with the use of heavy oil as the carbureting medium, in a gas-making set including a generator, carbureting apparatus, a conduit con-

necting the generator and the carbureting apparatus, and flow-direction control valves disposed exteriorly of the generator and carbureting apparatus and the conduit connecting the same, consisting in first upwardly blasting the fuel bed in the generator with air admitted at the bottom of the generator and burning the blast gases in the carbureting apparatus with air admitted to the latter and passed therethrough, then effecting a steam run upwardly through the fuel bed with steam admitted at the bottom of the generator and simultaneously spraying heavy oil upon the top of the fuel bed, and passing the resultant gaseous products through the carbureting apparatus, then effecting a steam run downwardly through the fuel bed with steam admitted at the top of the generator and withdrawing the resultant gaseous products from the set at the bottom of the generator, and then blasting downwardly through the fuel bed with air admitted to the set adjacent the top of the generator only and removing the blast gases from the set at the bottom of the generator.

2. The process, as set forth in claim 1, in which the upward blasting terminates with a short up-blow run after shutting off the air being admitted to the carbureting apparatus.

3. The process, as set forth in claim 1, in which the spraying of heavy oil upon the top of the fuel bed is continued into and through a part of the down steam run.

4. The process of manufacturing carbureted water gas, with the use of heavy oil as the carbureting medium, in a gas-making set including generator, carbureter, and superheater shells, and a seal, conduits connecting said shells and seal in series, a conduit connecting the generator and the seal, and flow-direction control valves disposed in the respective conduits between the superheater and the seal and the generator and the seal, consisting in first upwardly blasting the fuel bed in the generator with air admitted at the bottom of the generator and burning the blast gases in the carbureter and superheater with air admitted at the top of the carbureter, and exhausting the waste gases from the set, then effecting a steam run upwardly through the fuel bed with steam admitted at the bottom of the generator and simultaneously spraying heavy oil upon the top of the fuel bed, and passing the resultant gaseous products through the carbureter and superheater to the seal, then effecting a steam run downwardly through the fuel bed with steam admitted at the top of the generator and conducting the resultant gaseous products directly from the bottom of the generator to the seal, then blasting downwardly through the fuel bed with air admitted to the set adjacent the top of the generator only and conducting the resultant products directly from the bottom of the generator to the seal, and then continuing the downward blasting and exhausting the blast gases from the set at the bottom of the generator.

5. The process, as set forth in claim 1, in which the steam for the down steam run is admitted to the carbureting apparatus, passed therethrough, and thence passed downwardly through the fuel bed in the generator.

WILLIAM E. STEINWEDELL.
